UNITED STATES PATENT OFFICE.

CASEY MARGARETHA BELDY, OF BROOKLYN, NEW YORK.

DESIGN FOR A BOX.

SPECIFICATION forming part of Design No. 25,706, dated June 30, 1896.

Application filed May 6, 1896. Serial No. 590,494. Term of patent 14 years.

To all whom it may concern:

Be it known that I, CASEY MARGARETHA BELDY, a citizen of the United States, residing at Brooklyn, in the county of Kings and State of New York, have invented a certain new and original Design for a Plush Box; and I do hereby declare the following to be a full, clear, and exact description of the design, such as will enable others skilled in the art to which it appertains to make and use the same, reference being had to the accompanying drawings, and to letters of reference marked thereon, which form a part of this specification.

15 My invention relates to a new and original design for boxes; and it consists in the outline and configuration whereby the box is given a novel and ornamental appearance, as will be more fully described hereinafter.

20 In the accompanying drawings, Figure 1 is a front elevation of a box which embodies my invention. Fig. 2 is a vertical cross-section of the same.

A represents the box proper, which has 25 sloping ends B and sides C, and is provided with the hinged stuffed cover D, which is adapted to be turned backward, as shown in dotted lines. A portion of the back F ex-

tends rigidly upward from the rear side of the box A, and fastened to this part F, by 30 the ribbons G, is the padded or stuffed portion H of the back, as shown. To the inner edge of the cover D and to the lower edge of the part H are also fastened ribbons I. The outline of the top and end edges of these two 35 parts of the back F H is shown in Fig. 1, being rounded up from the ends and curved downwardly at the center.

At each end of the box is placed a roll J, which is padded or stuffed and ornamented at its outer end by the ornament L and the tassels O. Along the top edge of the box A, where the cover D is hinged on, is secured an ornamental fringe P, as shown.

Having thus described my invention, I 45 claim—

The design for a box, substantially as shown and described.

In testimony that I claim the invention set forth above I have hereunto set my hand this 50 28th day of March, 1896.

CASEY MARGARETHA BELDY.
